UNITED STATES PATENT OFFICE.

ANTONE ALBERT ZALONDEK, OF CAPITOL HILL, OKLAHOMA.

SPARK-PLUG.

1,284,848.

Specification of Letters Patent. Patented Nov. 12, 1918.

Application filed February 13, 1913. Serial No. 748,185.

To all whom it may concern:

Be it known that I, ANTONE A. ZALONDEK, a citizen of the United States, and a resident of Capitol Hill, in the county of Oklahoma and State of Oklahoma, have invented a new and useful Improvement in Spark-Plugs, of which the following is a specification.

This invention relates to spark plugs, a device used in connection with internal combustion engines, and which, while in use, is subjected to the most severe taxation, especially from excessive heat, carbon corrosion, and which under the excessive heat will break the material necessary for insulation.

To this end, therefore, an object of the invention is to provide means for preventing the heat from reaching the insulation, to also prevent the carbon from rendering the device inoperative, and to lengthen the life of the spark-creating medium.

In connection with such object, an important object of the invention is to provide an elongated or extended dead-air chamber, in connection with a spark plug, that will be instrumental in preventing the exploded charge from reaching to the plug insulation. Oils and greases have a tendency to short-circuit the plug, rendering the same inoperative, and these substances usually are shot against the plug during explosions, and to this end the said vacuum chamber will prevent the oil and grease from being thrown to the plug.

Other important objects of the invention will appear from a further reading of the following specification.

In the drawings:

Figure 1 is a side view of the improved spark plug,

Fig. 2 is a longitudinal section, and

Figs. 3 and 4 are sections on the lines 3-3 and 4-4 respectively of Fig. 2.

The present embodiment of the invention comprises a tubular casing 1 of conducting material, having its lower end externally threaded at 2, for engaging an opening in the cylinder of the engine, and just above the threaded portion the casing has an external surface 3, which is polygonal in cross section for the engagement of a wrench or the like to remove or insert the plug.

This tubular casing 1 is of sufficient length to insure a substantial column of air under pressure, so that a cushion is formed against which the explosion makes impact, thus pre-

venting the heated charge from reaching to the main and insulated portion of the spark plug, and what may be said of the explosion, is likewise true of the oil and grease and such other elements, such as carbon, as would naturally be forced to the plug under explosions, where a cushion chamber is not employed.

The upper end of the plug is enlarged both internally and externally to form internal and external annular shoulders 3 and 4. Just above the shoulder 3, the plug is internally recessed to form an internal annular shoulder 5, and the said plug is internally threaded as shown at 6 at the upper end of the recess.

A rod 7 of conducting material is arranged at the axis of the casing 1, and the said rod extends from the lower end of the said casing to beyond the upper end thereof. At its lower end the rod is provided with an angular lug 8 which extends radially of the casing and slightly upward as shown in Fig. 2 and into proximity to the inner surface of the casing.

The rod is insulated from the casing by means of a cylindrical plug 9 of porcelain or the like, the said plug having an external annular shoulder 10, intermediate its ends which engages the shoulder 5 to limit the inward movement of the plug with respect to the casing. A packing nut 11 is threaded into the casing at the upper end to hold the plug in place, the said packing nut having a flange 12 externally corrugated to facilitate the turning of the nut.

The plug has a central bore 13 through which the rod 7 extends and at the lower end of the plug the bore is enlarged as shown at 14, and shoulders 15 and 16 are formed at the junction of the enlarged portion with the main portion of the bore.

The rod is provided with annular ribs 17 and 18, the former fitting against the shoulder 15, and the latter against the shoulder 16, and the said ribs limit the upward movement of the rod with respect to the plug. It will be noticed that the rod is threaded above the rib 18 and the upper end of the plug 9 is reduced, and the reduced portion is engaged by a metallic fitting 19 in the usual manner.

A thumb nut 20 is threaded on to the upper end of the rod and the said nut is provided for clamping the terminal 21 of the cable 22 that connects the plug with the

source of electrical energy between the said nuts and the metallic fitting 19, before mentioned.

A packing 23 is arranged on opposite sides of the shoulder 10 between the shoulder 5 and the inner end of the packing nut 11. The said packing bears against the shoulder 10 in both directions so that the said shoulder is engaged neither by the metallic shoulder 5 nor by the metallic inner end of the packing nut.

It will be noted that the tubular casing 1 extends a considerable distance below the lower end of the plug 9, and that the wall 15 of that portion of the casing below the ribs 3 and 4 is very thin. In the ordinary construction of spark plug, the lower end of the tubular casing is adjacent to the lower end of the insulating plug and the spark 20 gap is adjacent to the said lower end of the plug.

In the present construction the spark gap is spaced apart from the end of the plug. By this construction a dead air chamber is 25 provided between the spark and the insulating plug, wherein there is no combustion, and by this arrangement the only heat that reaches the insulation is due to the conduction. Since the greater portion of the casing 1 is in the open air, the casing will be cooled by the circulation of air so that but a very slight amount of heat will be imparted to the insulating plug.

The plug is thus protected from heat and 35 from carbon deposits. As is known, the most destructive element that acts upon the spark plug is the heat of the explosion. The insulation is overheated and as it cools or as it becomes heated it is very liable to crack, 40 and the spark plug may be short circuited from a crack that is not visible on the outside. With the present construction, the insulation is removed from the heated en-

gine and is so placed that a free circulation of air may take place around the same.

It will be evident that with a plug constructed as specified, the insulation will at no time become over-heated. But little heat can be imparted to the insulation by convection, since the gases between the spark 50 and the insulation will not readily distribute heat in this manner. In addition there can be but little heat imparted to the insulation by radiation, since the plug is in the open air, and in air that is circulating. On 55 account of the thinness of that portion of the wall of the tubular casing between the engine and the insulation but a slight amount of heat will be conducted to the insulation by conduction. The air that circulates around the outside of the tubular casing will receive the greater portion of the heat of conduction before it reaches the insulation.

I claim:—

A spark-plug, including an insulating plug, a casing containing said plug, an elongated rod or electrode extending longitudinally through said casing with its lower end terminating at the lower end of said 70 casing, the lower terminals of said insulating plug and rod being remotely spaced apart, means for sealing said plug within said casing, said casing having an elongated dead-air chamber therein between the plug 75 and its attaching end, the walls of the dead-air chamber of said casing being thinned or attenuated whereby the heat of conduction resulting from the sparking action will be neutralized by the outside cold air, and thus 80 be prevented from reaching the insulating plug.

ANTONE ALBERT ZALONDEK.
